LIQUID MIXER AND METHOD OF MIXING

George C. Gester, Jr., Berkeley, and Donald B. Sewell, Concord, Calif., assignors to California Research Corporation, San Francisco, Calif., a corporation of Delaware

Application March 8, 1951, Serial No. 214,554

6 Claims. (Cl. 259—9)

1

This invention relates to liquid mixers and methods of mixing and particularly refers to those in which two liquids of widely different characteristics are introduced into a confined housing and are distributed and agitated in such a manner that one liquid is finely divided and uniformly distributed throughout the other.

In the chemical treatment of liquids, for example certain petroleum distillates, with reagents such as sulfuric acid which are immiscible therewith, it is sometimes desirable that the reagent should be uniformly and finely dispersed throughout the oil, in very small drops, and that the mixture thus formed be quickly removed from the zone of agitation and mixing to what we term a reaction zone, in which the mixture is relatively quiescent, after which the reacted materials may be separated in any desired manner to remove acid reaction products, sludge, and the like from the treated oil. The differences in physical properties, such as viscosity, surface tension, and specific gravity of the liquids to be mixed renders this a somewhat difficult problem. Various arrangements of circular impellers, with and without serrations, notches, vanes, etc. have been prepared to be placed in circular housings of varied configurations and rotated to disperse and mix the bulk of the two or more liquids which are to be contacted. For a given degree of mixing these involve the expenditure of relatively large amounts of energy, most of which is spent in churning the bulk liquids which raises their temperature and is wasteful of power.

This invention comprehends broadly a method and means for mixing two liquids, for example oil and sulfuric acid, involving the formation of separate thin films of the liquids, for example by spreading them on opposite sides of a smooth, rapidly rotating disc, and merging the films in a laterally confined circular chamber, from which the resultant fine dispersion of acid in the oil may be removed quickly to a relatively quiescent reaction zone, after which the reaction products, oil, acid sludge, etc., may be separated by gravity, by centrifugal means, electrical means or any others that may be suitable. Desirably, but not necessarily, the merging thin films are subsequently agitated or broken up by means such as thin blades rotating substantially in the merging plane, and if desired these blades may be integral with or extensions of the disc on which the films are initially formed.

It has been found that, by utilizing this invention in lubricating oil processing, the greatest quantity of desired primary reaction products are

2

formed between the initial surface of the acid droplets and the untreated oil external to them, with a minimum of undesired secondary reaction between the unreacted acid at the center of the acid droplets and the primary reaction product layer just described. If these secondary reaction products are released from the composite droplets to enter the external oil phase, their presence therein has been found to be quite detrimental to the quality of the finished product. The cause of such release is generally long-continued or uncontrolled agitation, particularly in the case of bulk mixers, which continue to beat or to churn the mixture of unreacted oil and the composite droplets of acid surrounded by the desired primary reaction product layer. Another cause of secondary reaction products release to the external oil phase is long-continued or uncontrolled time of contact between the composite droplets and the external phase after the completion of the initial dispersion of the acid throughout the untreated oil. In addition to the advantages just described, the invention herein has been found to accomplish the required contact of the immiscible liquids with a minimum of mechanical energy input.

It is an object of this invention to provide a method of rapidly and completely dispersing one liquid within another liquid that is immiscible therewith.

Another object is to provide an improved method of dispersing a reagent liquid, such as sulfuric acid, within a liquid of dissimilar properties, such as a lubricating oil distillate, so that a subsequent chemical reaction between the two may be completed under controlled conditions to obtain a desired purifying or modifying action of the second liquid.

Another object is to provide a method of mixing an aqueous liquid within a non-aqueous liquid in very fine droplets, to give a maximum surface area to the dispersed phase aqueous droplets which are in reactive contact with the continuous phase non-aqueous liquid with a minimum of volume of said droplets.

Another object is to provide an improved mixer of simple and compact form and which will handle relatively large quantities of liquids with a minimum of power input.

These and other objects and advantages of the invention will be further apparent from the following description of a preferred form of the apparatus and the method of mixing embodied therein, taken in connection with the attached

drawing, which forms a part of this specification.

In the drawing,

Fig. 1 is a vertical sectional view taken in a plane at right angles to the plane of mixing;

Fig. 2 is a side elevational view on line 2-2 of Fig. 1, and illustrates one form of the rotor disc;

Fig. 3 is a side elevational view on line 3-3 of Fig. 1 and illustrates a preferred form of liquid-collecting and liquid-controlling means;

Fig. 4 is a schematic flow diagram of the method as applied to a sulfuric acid-lubricating oil distillate treating process.

Referring to the drawing, and particularly to Fig. 1, reference numeral 10 designates generally the housing of the mixer, in this example comprising a back plate 11 of suitable acid-resisting metal, such as a silicon-iron alloy, provided with a shallow recess 12 in one face. A first liquid inlet connection 13 in plate 11 conveys liquid to a system of distributor passages 14 communicating with recess 12 near its center. A rotor generally designated 15, also of suitable acid-resistant metal, is mounted upon shaft 16 which rotates in bore 17, sealed against leakage by packing gland 18 and is driven by any suitable power source (not shown) at relatively high speed, 1,000 to 15,000 R. P. M. The clearance between the bottom of recess 12 and the back face of rotor 15 is desirably small to provide a confined space for a purpose to be explained in more detail below.

The rotor 15 itself is formed with a generally disc-shaped center portion 19 and, in this example, has tapered and diametrically opposed blade portions 20 merging tangentially with and of substantially the same thickness as the center, the tips of the blade portions extending substantially to the outer diameter of recess 12. Desirably, both the disc-shaped center portion 19 and the blade portions 20 are provided with smoothly tapered or knife-like edges as at 21.

The cover plate 22 which completes the mixer housing 10 is of similar material to that of back plate 11 and is secured to the latter by means such as circumferentially spaced through-bolts 23. Plate 22 is also slightly recessed as at 24 and this recess may be provided with radial vanes 25. An inlet connection 26 for the second liquid is provided in the center of plate 22 and terminates in a restricted nozzle 27 which directs the second liquid onto the center of the disc-shaped portion 19 of rotor 15 to form a uniform, outwardly flowing, thin film thereon. Vanes 25 may assist in the uniformity of this flow by preventing the outwardly-flowing film from swirling due to rotation of rotor 15 in the confined space within the housing 10.

The outer edge of recess 24 in cover plate 22 is deepened as at 28 to form an annular mixture-collecting chamber from which the mixed liquids leave the housing 10 through outlet connection 29. In this example, annulus 28 is substantially entirely within cover plate 22 and at one side of rotor 15, for a purpose to be explained below, but, if desired, it may be formed partly in back plate 11 to be symmetrically disposed with respect to the plane of rotor 15.

In operation, the first liquid, in this example a lubricating oil distillate, is introduced into the housing 10 through connection 13 and is distributed by passages 14 to form a thin, outwardly moving film on the back face of the disc-shaped center portion 19 of rotor 15. At the same time the second fluid, in this case concentrated sulfuric acid, is introduced into housing 10 through

inlet 26 and is directed by nozzle 27 to form a thin, outwardly moving film on the front face of the disc-shaped center portion of rotor 15. As the two liquid films thus formed pass over the tapered knife-like edges 21 of rotor 15, they merge intimately, and immediately thereafter are violently sliced or sheared by the larger diameter blade portions 20. In the arrangement shown, with the annular mixture-collecting chamber 28 entirely

10 on the "acid side" of the rotor blade tips, it will be obvious that, before any of the first liquid (oil) entering the housing 10 through inlet 13 can leave the housing through outlet 29, it will have to pass through the merging plane swept by

15 blades 20 of the rapidly revolving rotor 15. To facilitate this, rotor 15 may be driven in the direction shown by the arrow, Fig. 2, which is opposite to the direction of the final liquid mixture through the tangential outlet 29 from annulus

20 28. In practice, with a mixer for an oil throughput of about 100 barrels/hour, having a 6-12 inch diameter rotor, the speed of rotation would range from 1,000 to 6,000 R. P. M., giving blade tip velocities of about 25 to 320 feet per second, at a power input, depending upon the speed, of only about 30 H. P. With smaller sizes, speeds up to 15,000 R. P. M. have been found desirable.

Referring now to the flow diagram of Fig. 4, reference numeral 31 designates the lubricating 30 distillate or oil supply tank, from which the oil passes through conduit 32 and pump 33 to inlet

35 13 of mixer 10. Acid is stored in tank 34 from which a fluid pressure source 35 forces it through conduit 36 to inlet 26 of mixer 10, the latter being driven by motor 37. Ratios of acid to oil may

40 range from 0.1 to 10 lbs. of acid to one gallon of oil. By suitable choice of proportions of the mixer, conduits and flow control means which are well known, it can be arranged that, immediately

45 after the mixing operation the mixture is passed through outlet conduit 38 to a relatively quiescent reaction zone 39 to remain in contact for the desired period of time. At the end of this time interval, which is controlled by the flow rate and the volume of zone 39, the reacted mixture passes

50 through conduit 40 to separator 41, which may be of a simple gravity type, or may be a centrifugal or electrostatic separator. From the separator 41 the treated oil may be removed from the system through conduit 43 and the waste products, sludge, etc., may be removed from the system through conduit 44. Alternatively, the mixture

55 may pass directly from mixer 10 through bypass 42 to separator 41, without passing through or remaining in reaction zone 39.

In conclusion, it will be appreciated that a method and means for mixing two liquids, which may be dissimilar in their several physical and chemical properties, have been described and illustrated. It is believed that the essential features of the invention reside in the formation of

60 separate, rotating, outwardly moving films of the liquids which are smoothly merged in a plane in a confined space, and are thereafter "sliced" or 65 sheared to form a fine suspension or dispersion of one liquid in the other, after which the mixture may be rapidly removed from the mixing zone to a relatively quiescent zone where the desired reaction, as in the case of acid and oil, may continue to take place for the optimum length of time.

70 Although a specific arrangement and mode of operation have been described and illustrated, it is obvious that numerous changes could be 75 made without departing from the essential fea-

tures of the invention, and all those that fall within the scope of the appended claims are considered to be embraced thereby.

We claim:

1. A method of mixing dissimilar liquids comprising the steps of forming separate rotating plane films of said liquids, merging said films in a plane and flowing the merged films radially outwardly in a confined path into a mixing zone to form an intimate dispersion of one liquid in 10 the other liquid.

2. A method according to claim 1, with the added step of mechanically shearing the merged film in the plane of their merging.

3. A method of treating oil with a liquid reagent that is immiscible therewith comprising the steps of forming separate rotating plane films of said oil and said reagent, merging said films in a confined path to form an intimate dispersion of the reagent liquid in said oil and removing the mixture into a reaction zone.

4. A method according to claim 3 with the added step of mechanically shearing the merged films in the plane of their merging.

5. Mixing apparatus for liquids comprising a housing defining a confined flat circular chamber, a smooth-faced disc-shaped rotor rotatable in said chamber, the periphery of said rotor being tapered inwardly from each face to a knife edge, a plurality of passages in said housing for admitting liquids to said confined chamber to direct them against substantially the center of said rotor and on opposite sides thereof to form outwardly

moving uniform liquid films thereon which smoothly merge in a single plane in said chamber, and a liquid outlet from the periphery of said chamber.

6. Mixing apparatus according to claim 5, in which said rotor is provided with radially directed blade portions of the same thickness as said rotor and merging tangentially with the central disc portion thereof, said blade portions extending substantially throughout the diameter of said chamber.
